PLATEN FOR PRINTING MACHINES AND THE LIKE

Filed Sept. 25, 1944

UNITED STATES PATENT OFFICE

2,479,521

PLATEN FOR PRINTING MACHINES
AND THE LIKE

Merritt G. Stewart, Chicago, Ill., assignor to Victor Adding Machine Co., Chicago, Ill., a corporation of Illinois

Application September 25, 1944, Serial No. 555,714

1 Claim. (Cl. 101—26)

1

My invention relates broadly to platens used in printing machines, such as checkwriters, and more specifically relates to platens used in connection with printing machines having type with scarifying type faces.

Heretofore, it has been customary in printing machines, such as checkwriters, to employ type faces having projections relatively spaced to register with complementary grooves or depressions in a metal platen, for marking checks, bonds or other commercial papers with an inked impression of the value thereof, or other indicia, so as to scarify or disrupt the fibers of the paper over the area to which the ink is applied, whereupon the paper will become impregnated with the ink and thus indelibly marked with the desired inscription.

While this type of platen is satisfactory in many respects it has several disadvantages. For example, such a platen is costly to manufacture, and unless accurate alignment is maintained between the platen and the scarifying type faces of the type, damage to the platen and/or type will occur.

Another form of platen which has been extensively used in the past for checkwriting machines employing type with scarifying type faces are platens having rubber, or a like resilient surface, which is pierced by the type face projections. While platens of this type are cheaper to manufacture than the metal platens, they have a relatively short life due to the fact that continuous piercing of its surface by the scarifying type faces has a tendency to cause such surface to become worn and pitted, and the quality of the printing becomes greatly impaired.

It is the broad purpose of my invention to obviate the foregoing objections found in present day platens, for printing machines, by providing a platen which is simple in construction, efficient in operation, economical to manufacture, substantially indestructible, and one which will greatly improve the quality of printing.

The invention had its conception in connection with a checkwriting machine employing type having scarifying type faces; but, as will be evident from the present disclosure, it is not limited to this particular kind of printing machine.

More limitedly, it is an object of my invention to provide a platen for printing machines, the type striking portion of which, is composed of tightly packed hairs which may be readily fabricated into a compact and sturdy structure possessing the features hereinbefore pointed out.

My invention, embodied in a platen for printing machines, is illustrated in the accompany-

ing drawing, and while I shall proceed to describe the same in detail it will be understood that the invention, in its broader aspect, is not limited to the structural details shown further than is required by the terms of the appended claim.

Still further objects and advantages, in addition to those already pointed out, will be apparent as the description proceeds in connection with the accompanying drawing in which:

Fig. 1 is a perspective view of one form of frame and hair retainer which may be employed in the manufacture of my improved platen.

Fig. 2 is a face view of the assembled platen which forms the subject matter of the present invention.

Fig. 3 is an end elevation of Fig. 2.

Fig. 4 is a vertical cross-section of the platen taken on a plane corresponding to the line 4—4 of Fig. 2.

Fig. 5 is a fragmentary side elevational view illustrating the preferred method of finishing the platen type-striking surface.

Fig. 6 is a face view similar to Fig. 2 but showing a modified platen frame where two spaced apart parallel type-striking surfaces are desired.

Fig. 7 is an end elevation of Fig. 6.

Fig. 8 is a highly magnified fragmentary view clearly illustrating the manner in which the scarifying type faces pierce the inking ribbon and paper and spread the tightly packed hairs of the platen surface, and,

Figs. 9 and 10 are front and side views respectively of a portion of one form of scarifying type which may be used in connection with my improved platen.

In the embodiment of my invention as shown in Fig. 2, my improved platen is designated, in its entirety, by the reference character A and comprises a body portion B rigidly supported within a frame C.

One convenient form in which the frame may be made is shown in Fig. 1 as comprising two elongated U-shaped metal parts 11 and 12, each of which have their free ends reduced in width to form ears 13. Part 11 has an end plate 14 rigidly secured thereto, as by spot welding shown at 15, and this plate is provided with slots 16 dimensioned to receive the ears 13 of part 12. One branch of part 11 has a wall 17 formed integrally therewith, and bent at a right angle thereto, which wall serves as a seat or support for the body B in a manner presently described.

Part 12 also has an end plate 18 secured thereto, preferably by spot welding shown at 19, and

slots 20 in said plate and end wall are dimensioned to receive the ears 13 of part 11 when the frame C is assembled.

Referring now to body B, I propose the use of tightly packed hairs, designated 21, which are clearly shown in Figs. 5 and 8. The hairs 21 are preferably of a length greater than the width of parts 11 and 12, as shown at the left hand side of Fig. 5, and while being held in packed relation, are inserted within the parts 11 and 12 of frame C and against the seat 17. While the hairs are being held in this manner, parts 11 and 12 are moved towards each other until the ears 13 of part 12 pass into the slots 16 in plate 14, and the ears 13 of part 11 pass into the slots 20 of part 12 and plate 18, at which time the ears are bent over as shown in Figs. 2 and 3. Thus the frame C tightly embraces the body B of hairs 21 with one end of each individual hair 21 resting upon the seat 17 and its other end protruding above the upper edges 22 of parts 11 and 12 as best shown in Fig. 5.

The next step involved in the formation of the platen shown in Fig. 2 is to trim the exposed ends of hairs 21 closely to the upper edges 22 of frame C in any suitable manner, as for example by a cutting element such as the knife 23. I have found that after this trimming operation of the hairs 21, a good type-striking surface is obtained, but if a harder surface is desired, the ends of hairs 21 may be ground substantially flush with said upper edges 22 of frame C by an abrasive wheel shown at 24.

With the foregoing in mind attention is now directed to the highly magnified view shown in Fig. 8, and to Figs. 9 and 10 which illustrate a fragmentary portion of conventional type 25 having scarifying type faces 26. These type faces usually include pyramidal or needle-like projections 27, which during a printing operation, pierce the inking ribbon, shown at 28, and the check or paper 29 being printed upon, and backed up by the body portion B of the platen A.

It will be clear from Fig. 8, that when the pointed projections 27 pass through the ribbons 28 and paper 29 to engage the platen surface, the exposed ends of hairs 21 will be slightly parted, as shown, and when such projections are removed, from the platen body B, the hairs 21 will snap back to their normal position. It follows therefore, that as the projections 27 of type 25 pierce the platen, its surface will not be exceedingly worn or pitted due to the yielding action of hairs 21, in the manner just described.

The modified platen shown in Fig. 6 is formed in substantially the same manner as that described in connection with Fig. 2, and therefore a detailed description is deemed unnecessary. Suffice it to say that in this form the platen has a double surface designated D and E for pur-

poses well known to those skilled in the art of checkwriting and like printing machines.

While I have shown and described a particular embodiment of my invention it will be apparent to those skilled in the art that numerous modifications and variations may be made in the form and construction thereof, without departing from the more fundamental principles of the invention. I therefore desire, by the following claim, to include within the scope of my invention all such similar and modified forms of the apparatus disclosed, by which substantially the results of the invention may be obtained by substantially the same or equivalent means.

Having thus described my invention what I claim as new and desire to secure by Letters Patent is:

In combination in a printing machine, type having scarifying faces, and a platen for backing up printing-receiving material and providing a suitable type-striking surface for the scarifying faces of type, comprising a plurality of hairs disposed in parallel relationship with the ends thereof in a plane to form said type-striking surface, and a frame surrounding said hairs and holding them in tightly packed condition, an edge of said frame being disposed substantially in the plane of said type-striking surface to insure the surface forming ends of said hairs being maintained in the desired tightly packed condition by preventing spreading of said hairs beyond the confines of said frame.
